CATHODE ASSEMBLY FOR ELECTRON
DISCHARGE DEVICESCharles V. Litton, Grass Valley, Calif., assignor to Litton
Industries, Inc., Beverly Hills, Calif., a corporation of
Delaware

Application November 15, 1954, Serial No. 468,956

3 Claims. (Cl. 313—344)

This invention relates to a cathode assembly for electron discharge devices, and more particularly to a telescoped cathode assembly of great rigidity which employs a filamentary cathode. Although, in general, the cathode assembly of the invention may be employed in various types of vacuum tubes, it is particularly useful in multi-cavity magnetrons which employ a filamentary cathode of the bifilar type, and the preferred embodiment of the invention will therefore be illustrated and described in connection with a vacuum tube of this type.

Filamentary cathodes of the bifilar type are in general well known to the electron art, and are employed to serve several useful functions. Firstly, utilization of two counter-energized helical filaments substantially eliminates the extraneous magnetic field which is normally generated by a single helical wound filament. Secondly, a bifilar filamentary cathode provides a 3-terminal center-tapped cathode assembly the central terminal of which may be employed for modulating the flow of electrons emitted from the cathode.

Although bifilar filaments have heretofore found extensive use in the vacuum tube art in general, their use in the magnetron art has been complicated heretofore by several factors. For example, the 3-terminal cathode assemblies utilized in the prior art for mounting filamentary cathodes are unusually lengthy and bulky owing partly to the requirement that all three of the cathode terminals of a magnetron be well insulated and spaced from the main housing assembly which constitutes the anode terminal, and partly from the fact that each of the three terminals must be spaced axially from the other two terminals in order to facilitate the making of electrical connections to the terminals. In addition, the utilization of a bifilar filamentary cathode with its concomitant lengthy terminal assembly intensifies the problem of maintaining the cathode in a rigid position relative to the associated magnetron anode.

In the prior art one significant advance has been made which offers at least a partial solution of the problem set forth above. This prior art structure involves the use of a pair of concentrically mounted conical frustums for supporting the cathode, the frustums being so shaped at their apical ends to present a pair of complementary semi-circular terminals for respectively connecting to the two windings of the cathode. This particular form of cathode assembly is disclosed in U.S. Patent No. 2,474,263, issued June 28, 1949 to Charles V. Litton.

Although the aforementioned prior art cathode assembly has been successful in proving the utility of employing bifilar filamentary cathodes in magnetrons, it is nevertheless limited by several inherent disadvantages. Firstly, the resulting cathode assembly is still relatively lengthy owing to the fact that the three cathode terminals are axially spaced from each other by relatively large distances. Secondly, each of the terminals includes a threaded collar to provide a terminal surface which may be engaged by the corresponding connecting terminals of an associated tube socket. Thirdly, the filamentary cath-

ode is still susceptible to vibration owing to the relatively large overall length of the cathode assembly.

The present invention, on the other hand, obviates the above and other disadvantages of the prior art cathode assemblies by providing a relatively short 3-terminal cathode assembly of exceptional rigidity and one in which electrical connection is made directly to the terminals without the utilization of additional components. According to the basic concept of the invention, there is provided a unitary cathode assembly in which the terminal subassembly includes three concentrically mounted and axially spaced annular terminal members which are telescoped so as to be connectable directly to the elements of an associated tube socket without employing any additional collars or sleeves.

More particularly, according to the invention each of the three annular terminal members is of a different size and includes first and second sleeve-like end regions having different diameters, the end regions being separated by an S-shaped central region which telescopically interconnects the two end regions. The first or largest terminal member is coupled at its large end to the magnetron anode housing through a first glass sleeve, and is coupled at its smaller end to the large end of the second or intermediate terminal member through a second glass sleeve. Similarly the smaller end of the second terminal member is coupled to the large end of the third or smallest terminal member through a third glass sleeve, the smaller end of the third terminal member being enclosed to define in combination with the other terminal members and the associated glass sleeves a hermetically sealed cathode terminal assembly.

The S-shaped central region of each of the terminal members is so oriented with respect to the large end of the terminal member that a portion of the central region protrudes radially from the magnetron axis a distance larger than the outside radius of the glass sleeve connected to the larger end of the terminal member. In this manner each of the terminals may be engaged by the elements of an associated tube socket without interference from the adjacent glass sleeve.

It is therefore an object of the invention to provide a 3-terminal magnetron cathode assembly wherein the terminals are formed to provide a telescoped terminal subassembly, each pair of adjacent terminals being separated by an associated glass sleeve.

Another object of the invention is to provide a relatively short and rigid 3-terminal cathode assembly in which the terminals are composed of annular members having sleeve-like end regions of different diameters and an S-shaped central region to provide a telescoped terminal assembly in which connection can be made to each terminal without interference from adjacent insulative supporting members.

A further object of the invention is to provide a 3-terminal magnetron cathode assembly including a bifilar type filamentary cathode, the assembly including three concentrically mounted and axially spaced annular members which constitute the cathode terminals, each of the annular members being insulatively supported by an associated glass sleeve and having an S-shaped central region which protrudes radially from the magnetron axis a distance larger than the radial distance from the magnetron axis to the external periphery of the associated glass sleeve.

The novel features which are believed to be characteristic of the invention, both as to its organization and method of operation, together with further objects and advantages thereof, will be better understood from the following description considered in connection with the accompanying drawing in which one embodiment of the invention is illustrated by way of example. It is to be

expressly understood, however, that the drawing is for the purpose of illustration and description only, and is not intended as a definition of the limits of the invention.

With reference now to the drawing, there is shown in the figure a sectional view of a preferred embodiment of a cathode assembly, according to the invention, which includes a hermetically sealed terminal subassembly, generally designated 10, and a cathode support subassembly, generally designated 12, for rigidly supporting and providing electrical connection to the bifilar filamentary cathode of a cathode subassembly, generally designated 14.

According to the invention, terminal assembly 10 includes three annular terminal members 18, 20 and 22, respectively, which are hermetically sealed to and insulatively separated by two glass sleeves 24 and 26. In addition, the terminal assembly includes a third glass sleeve 28 which is hermetically sealed at one end to terminal member 22 and at its other end to a magnetron housing member 30, only a portion of which is shown.

Each of terminal members 18, 20 and 22 is preferably constructed of Kovar or a similar alloy whose coefficient of thermal expansion closely approximates that of glass, and includes two sleeve-like end regions of different diameters which are separated by a central region having an S-shaped cross-sectional configuration. It will be noted that the smaller ends of terminal members 22 and 20 are substantially identical in size with the large ends of terminal members 20 and 18, respectively, thereby permitting the use of cylindrical glass sleeves for insulatively interconnecting the terminals. It will also be noted that terminal member 18 is enclosed at its smaller end.

As shown in the figure, the S-shaped central region of each of the terminal members is so oriented with respect to its associated end regions that it protrudes radially beyond the external periphery of the glass sleeve which is affixed to the larger end of the terminal member. In this manner a tube socket including three concentric cylindrical arrays of contact springs may be utilized for making electrical connection to terminal members 18, 20 and 22 without interference from the adjacent glass sleeves, and without the utilization of additional metal sleeves or collars as required in the prior art. With reference to the figure, for example, there is illustrated by three connector elements 32, 34 and 36, respectively, how the contacts of a tube socket of the above type would engage terminal members 18, 20 and 22, respectively.

The S-shaped central regions of the terminal members also serve the additional function of telescoping the end regions of the terminal members, thereby materially decreasing the axial length of the cathode assembly of the invention. In practice it has been found that cathode assemblies constructed in accordance to the principles of the invention are several inches shorter than corresponding cathode assemblies constructed in accordance with the prior art technique.

The glass sleeves employed for insulatively mounting terminal members 18, 20 and 22 are preferably composed of relatively hard glass in order to provide a mechanically rugged structure capable of withstanding the relatively hard vacuums established within the chamber defined by terminal assembly 10 and the associated magnetron housing. The length of glass sleeves 24 and 26 should preferably be such that adjacent terminal members are separated by a distance of the order of .050 of an inch after the terminal members have been sealed to the sleeves. Glass sleeve 28, on the other hand, must be relatively long in comparison with the other glass sleeves, since sleeve 28 must be capable of withstanding the relatively high anode-to-cathode potential normally applied to an operating magnetron. A typical overall length for each of sleeves 24 and 26 is $5\frac{1}{16}$ of an inch, while sleeve 28 is preferably $1\frac{1}{8}$ inches in length, thereby providing a separation between terminal member 22 and magnetron housing 30 of approximately $1\frac{1}{4}$ inches. It will be recognized, of course, that the particular dimen-

sions selected for the various elements of the terminal assembly are determined in view of the desired position of cathode subassembly 14 relative to the magnetron anode and by the dimensions of the elements of cathode support subassembly 12.

Cathode support subassembly 12 includes three supporting members 38, 40 and 42 for electrically interconnecting terminal members 18, 20 and 22, respectively, with cathode subassembly 14 and for rigidly maintaining the position of the cathode relative to the associated magnetron anode, not shown. Supporting members 40 and 42 are preferably two conical frustums constructed in accordance with the principles disclosed in the aforementioned Patent 2,474,263 to Charles V. Litton, and are so dissected to provide at their apical ends two spaced, conjugate, semicircular supports which are connected to the left hand end of the cathode subassembly, as viewed in the figure. Supporting members 40 and 42 are preferably constructed of molybdenum or a similar material having a relatively low coefficient of thermal expansion, and are affixed at the periphery of their larger ends to terminal members 20 and 22, respectively, as by brazing, for example. Supporting member 38 is preferably composed of a hollow rod of molybdenum or a similar material, and is brazed at one end to terminal member 18, the other end of supporting member 38 having a shouldered hole bored therein to provide a recess for receiving a cooperating element of cathode subassembly 14. The holes 44 and 46 bored through supporting member 38 are provided to insure that the interior of the member is also evacuated when the magnetron employing the cathode assembly of the invention is outgassed or exhausted.

Cathode sub-assembly 14 includes a bifilar type filamentary cathode having two helical windings which are designated 50 and 51, respectively, the right hand end of each winding, as viewed in the figure, being electrically and mechanically connected to a common connecting member 52. This connecting member is, in turn, fixedly attached as by welding or brazing, to a center rod 54 which is composed of tungsten, for example, the center rod being seated in and rigidly held by the central supporting member 38. As shown in the figure, connecting member 52 may be grooved to improve its heat-dissipating properties.

The other ends of cathode windings 50 and 51 are respectively connected to two semicylindrical connecting members 56 and 58 which, in turn, are brazed to the apical ends of supporting members 40 and 42, respectively. Connecting members 56 and 58 are preferably constructed of molybdenum and, as shown in the figure, are spaced from center rod 54 and from each other by finite distances in order to prevent short circuiting of the cathode windings.

Connecting member 56 also includes a shoulder 60 which is utilized for fixedly supporting an annular end-hat member 62, the end-hat member being spaced from connecting member 58 and including a flanged end 64 for restricting to a predetermined region the electron emission into the magnetron interaction chamber. The left hand end of connecting member 52, as shown in the figure, is also flanged to provide a second end-hat for restricting the effective region of emission at the other end of the cathode. Both end-hat 62 and connecting member 52 are preferably constructed of zirconium coated molybdenum with a platinum coating over their flanged portions.

It will be recalled that connecting members 56 and 58 are spaced from each other and from center rod 54 in order to prevent short circuiting of one or both of the cathode windings. It has been found that during operation of the magnetron there may be a tendency for free electrons to pass through the slot between connecting members 56 and 58 and energize structural parts of the magnetron other than the anode, thereby tending to generate oscillations at an undesired frequency. Accordingly, the left hand end of end-hat member 62, as viewed

in the figure, is extended axially along connecting members 56 and 58 a distance sufficient to prevent the emission of electrons from the slot therebetween.

As set forth hereinabove the cathode comprises two filamentary windings 50 and 51 which are so mounted and energized as to constitute a bifilar filament. The windings are preferably constructed of carburized thoriated tungsten and are energized so that current in adjacent turns flows in opposite directions with the result that the magnetic field produced by the cathode current is substantially neutralized. Accordingly, if alternating current is applied to energize the cathode, as is often the case in practice, the small amount of residual alternating flux produced by the cathode is insufficient to appreciably modulate the electrons emitted from the cathode.

In operation power for energizing the filamentary cathode is applied to terminals 20 and 22 to energize the two cathode windings in series. It will be recognized, therefore, that terminal 18 and its associated supporting and connecting members constitute a cathode center tap which may be utilized, if desired, to modulate the electron emission from the cathode windings.

It will be recognized from the foregoing description that the present invention provides a rigid 3-terminal magnetron cathode assembly which is relatively compact and in which electrical connection may be made directly to each of the three terminals without the utilization of additional components. In addition, it will be recognized that the utilization of a telescoped terminal subassembly foreshortens the entire cathode assembly and functions to materially increase the rigidity of the overall structure while simultaneously decreasing the sensitivity of the cathode assembly to temperature changes.

What is claimed as new is:

1. A cathode assembly for an ultra-high frequency electron discharge device, said cathode assembly comprising: a bifilar filamentary cathode including first and second helical windings each having first and second ends; a terminal subassembly including first, second and third annular terminal members having a common axis, first and second insulative sleeves insulatively interconnecting and concentrically mounting said first and second terminal members with said second and third terminal members, respectively, and a third insulative sleeve insulatively interconnecting said third terminal member with the housing of the electron discharge device, each of said terminal members including two end regions of different diameters interconnected by a telescoped S-shaped central region a portion of which reverses direction with respect to said common axis, the smaller ends of said second and third terminal members being substantially equal in diameter with the larger ends of said first and second terminal members, respectively, said S-shaped central region of each of said terminal members protruding radially from the common axis of said members a distance larger than the outside radius of the glass sleeve which is connected to its larger end region to provide a protruding annular contact surface adopted to engage a contact member of an associated tube socket; and means connected to said terminal members and to said filamentary cathode for mechanically mounting said cathode and electrically interconnecting said cathode windings to said terminal members.

2. In a cathode assembly for utilization in a vacuum tube generator of ultra-high frequency electrical signals, a terminal subassembly for providing external electrical connection to an internally mounted cathode, said terminal subassembly comprising: first, second and third annular terminal members, each of said members includ-

ing a large end region and a small end region telescopically interconnected by a central region said central region having an S-shaped cross sectional configuration a portion of which reverses direction with respect to said end regions, the larger ends of said first and second terminal members having diameters substantially equal to the diameters of the smaller ends of said second and third terminal members, respectively; first and second glass sleeves insulatively interconnecting the larger ends of said first and second terminal members to the smaller ends of said second and third terminal members, respectively, and a third glass sleeve insulatively interconnecting the larger end of said third terminal member to the housing of the vacuum tube generator, said terminal members and said glass sleeves being concentrically mounted about a common axis and said S-shaped central region of each of said terminal members protruding radially from said common axis a distance larger than the outside radius of the glass sleeve which is connected to its associated end region to provide a protruding annular contact surface adopted for engagement by a terminal of an associated tube socket.

3. A cathode assembly hermetically sealed to the anode housing member of a magnetron, said cathode assembly comprising: a cathode element having first, second and third terminals for receiving electrical energy; a terminal subassembly hermetically sealing the anode housing member and providing external electrical connection to said cathode element, said terminal subassembly including first, second and third annular members, each of said terminal members including a large end region and a small end region telescopically interconnected by a central region, said central region having an S-shaped cross sectional configuration a portion which reverses direction with respect to said end regions, the larger ends of said first and second terminal members having diameters substantially equal to the diameters of the smaller ends of said second and third terminal members, respectively, first and second glass sleeves insulatively interconnecting the larger ends of said first and second terminal members to the smaller ends of said second and third terminal members, respectively, and a third glass sleeve insulatively interconnecting the larger end of said third terminal member to the anode housing member, said terminal members and said glass sleeves being concentrically mounted about a common axis, the portion of said S-shaped central region adjacent the larger end of each of said terminal members protruding radially a distance larger than the outside diameter of the glass sleeve connected to said larger end to provide a protruding annular contact surface adapted for engagement by a terminal of an associated tube socket; and rigid supporting means connected between said first, second and third terminal members and said first, second and third terminals of said cathode, respectively, said supporting means fixedly maintaining the position of said cathode relative to the anode housing member and being electrically conductive whereby the application of electrical signals to said terminal members electrically energizes said cathode.
